UNITED STATES PATENT OFFICE.

HAROLD S. WILLIAMS, OF CALDWELL, IDAHO.

FLUME OR CONDUIT.

1,092,315.

Specification of Letters Patent.

Patented Apr. 7, 1914.

Application filed April 10, 1913. Serial No. 760,118.

To all whom it may concern:

Be it known that I, HAROLD S. WILLIAMS, a citizen of the United States, residing at Caldwell, in the county of Canyon and State of Idaho, have invented certain new and useful Improvements in Flumes or Conduits, of which the following is a specification.

My invention relates to improvements in metal flumes and among the objects of my invention is the provision of a metal flume specially designed for purposes of irrigation, which will be of the simplest and cheapest possible construction, which will be readily assembled and taken apart when desired, which will provide an absolute watertight joint or connection between the sections, which can be adjusted to suit conditions, which will allow for the usual expansion and contraction, and which from every point of view will be thoroughly efficient and practical.

With the attainment of these objects in view, my invention consists of a metal flume composed of sections embodying novel features of construction and combination of parts, substantially as disclosed herein.

In order that the construction in detail and the advantages of my invention may be fully understood, I have illustrated in the accompanying drawing a metal flume embodying my invention.

Figure 1 represents a transverse sectional view of a metal flume constructed in accordance with my invention. Fig. 2 represents a vertical central longitudinal sectional view of the flume, and Fig. 3 represents a perspective view on an enlarged scale of the clamp or binder forming a part of my invention.

In the drawings: the letter A designates the longitudinal sills or supports, and B designates the transverse supports or cross pieces mounted upon the longitudinal sills, and it will be understood that the flume may be supported above the ground or may be placed in a trench or ditch, as conditions require.

The flume proper is composed of a series of metal sections C which have their overlapping ends D curved or bent in opposite directions to form the space E between said sections, and in said space is placed the packing or strip F, and thus when the sections are connected an interlocking joint

is made, which joint while permitting the usual play of expansion and contraction, provides an absolutely water-tight joint between the sections.

Passing around the sections at each joint is the curved clamping rod G, having its upper ends threaded at H, and receiving the securing nuts J. The upper ends pass through the cross pieces, and also through the openings K in the inward extensions or ears L of the binders M. Said binders are provided with the depending portion M' formed with the rib or web M², which serve to strengthen the depending portion M, which binders are also provided with the recess N, which receives the upper edges of the sections with the interposed packing, and when the securing nuts are screwed home, the binders serve to secure the sections in proper positions with reference to the tie rods, while to prevent improper movement of said binders their upper faces O are each provided with a rib P, which sinks into the surface of the underside of the cross pieces and serves to retain the binders from lateral movement.

From the foregoing description, taken in connection with the drawing, it will be evident that my flume can be quickly assembled or taken apart, that it is capable of the proper adjustment to secure a water-tight flume, and that the construction is the embodiment of simplicity and cheapness.

I claim:

1. In a metal flume or conduit, the combination with the longitudinal rails and the transverse strips supported thereon, of the binders having the lateral extension formed with an opening, the inward extension having a rib on its upper face to bite into the transverse strips and having the depending portion forming a recess or seat, the flume sections having their ends overlapping and fitting within the said recesses of said binders, and the tie rods passing around the ends of the flume and having threaded ends passing through the openings in the lateral portions of the binders, and securing nuts on said threaded ends.

2. In a metal flume or conduit, the combination with the longitudinal rails and the transverse strips supported thereon, of the binders having the lateral extension formed with an opening, the inward extension having a rib on its upper face to bite into the

transverse strips and having the depending portion forming a recess or seat, the flume sections having their ends overlapping and fitting within the said recesses of said binders and bent to form a space at said ends, packings in said space, and the tie rods passing around the ends of the flume and having threaded ends passing through the openings

in the lateral portions of the binders, and securing nuts on said threaded ends.

In testimony whereof I affix my signature in presence of two witnesses.

HAROLD S. WILLIAMS.

Witnesses:

F. D. MUMFORD,
OPAL STEWART.
